HAT WORKING MACHINE

Marcel Cassé, Essonnes, France

Application October 12, 1931, Serial No. 568,463
In France December 24, 1930

22 Claims. (Cl. 223—30)

The present invention has for its object a lathe mechanism for pieces whose sections have an oval, cycloidal, epicycloidal, hypocycloidal, or equivalent shape.

5 The invention also relates to various applications of one or several of these mechanisms taken in combination and, particularly, to machines used in connection with the hat making industry for the pouncing, brushing, glazing, ironing, etc. of hats.

The mechanism according to the present invention is chiefly characterized by the fact that it comprises in combination:

(a) A group of three parallel axes, located in 15 the same plane, journalled in a rigid organ such as a connecting rod or the like;

(b) A fourth auxiliary axis, parallel to the three above mentioned axes and journalled at 20 a fixed point on a straight line at right angles to said axes and capable of receiving the tool or the piece of work;

(c) The following connections between said elements (any of said elements may be fixed in space, the others maintaining said connections): 25 two of the axes of the above mentioned group are connected together by a transmission such that the algebraic ratio of their speeds of revolution is equal to the reciprocal of the ratio of the respective distances from said two axes to 30 the third axis of the group, said speeds of revolution and said distances being counted algebraically, that is, with regard to their signs as well as to their magnitudes; one of said axes thus connected to each other is further rigidly 35 connected to the auxiliary axis, the other one of said two axes being adapted to receive the piece of work or the tool; the third axis of the group is adapted to slide and to be journalled on the above mentioned straight line at right 40 angles to the axes.

The invention will be hereinafter described with respect to accompanying drawings, given merely by way of example, and in which:

Fig. 1 is a diagrammatical view of a mechanism, 45 adapted to trace cycloids, epicycloids, and curves parallel to said cycloids;

Fig. 2 is a similar diagrammatical view of a mechanism adapted to trace hypocycloids and curves parallel to said hypocycloids;

50 Fig. 3 is an elevational view, partly in section, of an apparatus in which the tool describes a cylinder whose cross section is a hypocycloid;

Fig. 4 is a plan view showing one half of the mechanism in section on the line 4—4 of Fig. 3;

55 Fig. 4a is a plan view showing one half of the

mechanism in section on the line 5—5 of Fig. 3;

Fig. 5 is a diagrammatical view of a tool holder in which every point of the tool describes, in its plane, a closed curve;

Fig. 6 is a vertical longitudinal section of a 5 machine according to the invention;

Fig. 7 is a front view of said machine;

Fig. 8 is a horizontal section on the line 8—8 of Fig. 6 of the lathe mechanism for oval turning;

Fig. 9 is a section on the line 9—9 of Fig. 6 of 10 said mechanism;

Fig. 10 is a partial end view;

Fig. 11 is an elevational view showing the pawls of the mechanism for starting the machine and reversing the displacement of the tool; 15

Fig. 12 is a plan view of the cam permitting to vary the oval described by the block that serves to support the hat;

Fig. 13 is a plan view of the cam permitting to vary the pressure exerted by the tool on the hat 20 and the speed of the engine for driving said tool;

Fig. 14 is a vertical section of another embodiment of a pouncing tool;

Fig. 15 is a plan view of another embodiment 25 of the pouncing tool driving mechanism;

Fig. 16 is an elevational view showing the arrangement of an electrical safety circuit breaker, disposed on the feed circuit of the electric motor of the machine. 30

Description of a mechanism according to the invention for tracing epicycloids

The mechanism according to the invention essentially comprises (Fig. 1) a group of three parallel axes A, B, C, at right angles to the plane of the figure. Said three axes are journalled in connecting rod indicated by straight line ABC. Axes A and B are connected through any suitable transmission (toothed wheels, connecting rods, chains, sliding members, and so on) so that the algebraic ratio K of the speed of revolution of axis A to that of axis B may be equal to the ratio

CB
CA

45 of the distances from axis C to axes B and A, said speeds of revolution and said distances being counted algebraically, that is with regard to their 50 signs as well as their magnitudes.

Furthermore, axis B is rigidly connected through a crank or any other similar organ BE to an auxiliary axis E, parallel to axes A, B and C. Said axis E is journalled at a fixed point of 55

a straight line L, at right angles to axes A, B, C, E. Finally axis C is so mounted as to slide and to be journalled on said line L.

5 A piece of work is fastened to axis A, and a tool O is fixed to straight line L, or reversely.

Any one of the elements of the mechanism: the four axes A, B, C, E, straight line ABC, straight line L, may be stationary the other elements being connected thereto and to each other as indicated. If we consider a first system S integral with axis A and a second system S' integral with axis B, and if we trace in system S a circle R whose radius is AC, and in system S' a circle T having a radius BC, when the systems S and S' move relatively to each other, said circles R and T roll one on the other. On account of the fact that the speeds of revolution of axes A and B are in a ratio which is reciprocal to the ratio of the radii, taken with regard to both magnitude and sign, said rolling displacement takes place without sliding. It results therefrom that point E, which is integral with axis B, belonging to system S' and moving with circle T describes in system S an epicycloid Y and that the point of contact C of the two circles is the center of instantaneous rotation of the displacement. Straight line L is therefore the normal to said epicycloid and a point O of said line describes a curve Y' which may be deduced from epicycloid Y by adding a constant length EC upon line L at every point E of the epicycloid.

If a piece of work is fixed upon axis A, it will therefore be presented to tool O in such manner that said tool will trace an epicycloid Y or a curve Y' parallel to said epicycloid. The tangent to said curve at the point of contact with the tool is constantly at right angles to the direction of the tool holder.

40 *Description of a theoretical embodiment of the mechanism for the tracing of hypocycloids*

Fig. 2 shows, in a diagrammatic manner, how a hypocycloidal mechanism may be obtained. Said Fig. 2 includes, same as Fig. 1, axes A, B, C, E and straight line L. Axis A is supposed to be stationary, same as an internal gear wheel whose radius is AC. Rod ABC rotates about A. A pinion whose axis is B is driven by straight line ABC and constantly meshes with the stationary internal gear wheel having its center at A. Axis E is integral with the pinion and it actuates a connecting rod representing line L which is adapted to both pivot and slide about axis C. Said rod L is integral with the axis of oscillation O of the tool and said tool envelopes the hypocycloid Y described by point E.

55 *Example of a practical embodiment of the theoretical mechanism of Fig. 2*

60 In Figs. 3 and 4 is shown a practical embodiment of the mechanism of Fig. 2 for driving a tool 1 of any type whatever which is to move along the whole lateral surface of a piece 2 whose cross section is the half-hypocycloid M—N—P of Fig. 2 for instance. Piece 2 is for instance given a rectilinear reciprocating motion in the direction of the axis of the cylinder. Tool 1 must therefore move in front of said piece so as to remain constantly tangent thereto. The point of contact Q 65 of the tool must therefore describe the half-hypocycloid M—N—P.

70 Tool 1 may for instance consist of a wheel keyed on a shaft 3 carried by a support 4. It is rotatably driven in any suitable manner, for instance by a motor 5 carried by support 4 or

75 directly mounted on shaft 3. Support 4 is pivoted about a horizontal axis 6 (axis O of Fig. 2) parallel to axis 3. A counterweight 7 tends to swing support 4 in the direction of arrow f¹ so as to apply grinding wheel 1 against the piece of work 2.

80 Axis 6 (O) is carried by a piece 8. Said piece 8 is rigidly connected, through rods 9 (Fig. 4) which extend through a piece 10 forming a casting (Figs. 3 and 4), to a piece 11 embodying straight line L of the diagrammatic system of Fig. 2. Said piece 11 is pivotally mounted about an eccentric journal 12 (axis E) of a spindle 13 (axis B). Piece 11 is provided with a guiding slot 14 in which slides a member 14^a pivoted 15 about an axis 15 carried by a piece 10 and a plate 16. Said plate 16, in which is journalled spindle 13, (axis B) embodies rod ABC of Fig. 2. It rests in a rotatable manner upon a circular cup-shaped element 17. Said element 17 comprises 20 an interiorly toothed portion 18 whose axis is 19 (axis A). A pinion 20, keyed on axis 13 (axis B) is adapted to mesh with said toothed portion 18. The diameter of said pinion 20 is one fourth the diameter of the toothed part 18. Pinion 20 further meshes with a pinion 21 mounted loose on shaft 19 and in mesh with a pinion 22. Said pinion 22 is keyed on an axis 23. A guide member 24 is keyed on said spindle 23, and a sliding element 25 pivoted about an axis 26 carried by a pinion 27 is adapted to move in said guide member 24. Said pinion 27 is mounted loose on a journal 28 eccentric with respect to axis 23. Pinion 27 is given the rotary motion through any suitable transmission means comprising a clutch 30 and a reversing device.

35 The operation of the device is as follows: Driven pinion 27 transmits the motion through guide member 24 to axis 23 and to pinions 22 and 20 which roll on inside gear 18. Axis 12 (axis E) therefore describes hypocycloid Y. Axis O, which is rigidly connected thereto, and also the point of contact Q of the tool which is mounted in the plane of axes E and O, are likewise displaced. If therefore the reverse gear is devised 45 in such manner that the direction of rotation of driving pinion 27 changes when point Q (center of the tool) reaches points M and P of the hypocycloid, and if the piece of work 2 reciprocates in the longitudinal direction, tool 1 will successively 50 come in contact with all the points of the lateral surface of said piece while remaining constantly tangent thereto.

55 The variation of the speed of the displacement of center Q of tool 1 along hypocycloid M—N—P is corrected by the system comprising eccentric pinion 27 and crank 24 because it is possible to vary the position of the connecting point (sliding element 25) of said system in such manner that the displacement of tool 1 with respect to the piece of work 2 may remain substantially constant.

60 *Combination of several mechanisms according to the invention*

65 It will readily be understood that several mechanisms can be combined in order to work on a piece upon the surface of which it is possible to define two series of sections in planes at right angles such that said sections may be cycloids or similar curves. The combination of two mechanisms will make it possible to present a plane tool in constant tangential relation to said surface. Hereinafter will be described a machine for the hat making industry comprising 70 such a combination. The advantages of said 75

combination result from the following considerations relative to the:

Movement of the pouncing tool of a pouncing device for polishing purposes in the hat making industry

Felt hats are pounced in order to obtain a smooth surface. That pouncing is a polishing operation which is performed by relative displacement of the felt hat and of an abrasive applied against each other. Said displacement is either continuous or reciprocating. It is continuous when the abrasive is a band of cloth or paper stretched upon a revolving drum or a belt moving with a translatory motion, or when the felt hat itself, stretched upon a rounded block or form, rotates with respect to the stationary abrasive. That process is too violent and some grains of abrasive may scratch the felt and produce a surface having parallel scratches. Furthermore some hairs of the felt are not cut but beaten down.

Finally, as the hat cannot be yet given its definitive shape the subsequent operations partly destroy the effects of the pouncing operation. Therefore, use is made of pouncing machines in which the paper moves in a rectilinear and reciprocating manner. It is thus possible to avoid bending down the hairs, but the scratches due to the rectilinear trajectory of the grains of abrasive cannot be wholly eliminated. Furthermore, the hairs and other particles that are detached from the felt agglomerate and form rolled masses interposed between the abrasive paper and the felt, which are difficult to eliminate, interfere with the abrasive, and produce dust and friction.

In order to obtain a smooth surface, the pouncing operation must be completed by hand, by giving the abrasive paper a substantially circular motion combined with a rectilinear displacement. Besides, any carefully done polishing of a material is effected in that manner. The present invention has for its object a pouncing tool which is given a movement similar to that of the hand of the workman and which ejects the products resulting from the pouncing operation as they are being formed.

Said tool essentially comprises a connecting rod crank mechanism (Fig. 5). Crank 29 is given its rotary motion through any suitable transmission, preferably an electric motor directly coupled, connecting rod 30 is pivoted to the crank pin of crank 29 either through a spherical bearing or equivalent system or through an ordinary bearing. It comprises a cylindrical tube 31 adapted to slide in the ball element 32 of a ball and socket joint, and a pouncing pad 33 rigidly secured to said rod 30 at a point different from the center of said ball and socket joint. It results therefrom that each of the points of said pouncing tool describes oval shaped trajectories in planes at right angles to the axis of driving crank 29.

If pouncing pad 33 is applied against the surface of a hat stretched upon its block, it will describe curves having a general circular shape, which are very similar to the displacement imparted by the hand of the workman, but provided that the plane of the tool is always substantially tangent to the surface of the hat. If that condition is not fulfilled, obviously, the movement of the pouncing pad in an oblique plane with reference to the plane tangent to the surface of the hat will produce irregular displacements detrimental to the perfection of the pouncing operation.

Now, the shape of the hats is such that the sections parallel to the base are ovals and that the sections at right angles to the base may be assimilated to a portion MN of a shortened hypocycloid having four retrogression points (Fig. 2).

Description of a machine for the hat making industry comprising two mechanisms of the above described type for pouncing, brushing, glazing, ironing, etc., hats

The machine according to the invention and shown in Figs. 6 to 13 comprises in combination two mechanisms according to the invention.

The pouncing tool is actuated in the same manner as the tool of Figs. 3 and 4, by a carriage, through the intermediary of an axis of oscillation O, which envelops a hypocycloid, in a plane at right angles to the base of the block.

As for the block that supports the hat, it is mounted on the spindle of an oval lathe which presents the oval sections of the hat parallel to the base in the suitable position, direction and speed. It results therefrom that the plane of the pouncing pad remains substantially blended with the tangent plane at each of the points of the surface of the block.

The machine further comprises connecting organs between these two mechanisms.

Description of the pouncing tool and of its driving mechanism

The pouncing tool is supported by a casing 35 articulated about a horizontal axis 6 (O) carried by the element 8 of a mechanism identical to that shown in Figs. 3 and 4 and above described. Preferably, elastic devices, for instance of the silent block or similar type, are interposed between axis 6 and the bearings of casing 35 as shown at 8a on Fig. 7.

The pouncing tool essentially consists of a steel tube 30 at the upper end of which is welded a box 36 made of iron sheets in which is disposed the elastic pad 33 upon which is stretched an abrasive paper 37 tightly held by nuts 38. The plane of pouncing pad 33 passes substantially through the axis of tube 30 and oscillation axis 6 (O).

Tube 30 slides in a ball and socket joint 32 carried by casing 35. At the lower end of said tube 30 is fixed a ball bearing 39 (Fig. 6), either of the swivel type or, preferably, rigid. The inner ring of said bearing is rigid with a crank shaft made of two pieces 40 and 41. Said crank shaft comprises keyed upon it two balancing counterweights 42. Said crank shaft is mounted on two ball bearings 43 and one of its ends projects outwardly from casing 35. Upon said end is keyed the wheel 44 of an exhauster and an electric motor 45 having a variable speed. A flywheel 46 is keyed on the shaft of said motor 45 so as to prevent, through its gyroscopic effect, rapid oscillations of casing 35 about axis 6.

Of course, any other suitable device might be used for playing the same part, that is, for damping the oscillations of the casing.

An aperture 48, through which the dust resulting from the pouncing can be drawn, is provided in casing 35 and conveys said dust to the outlet of wheel 44. Said dust is discharged into a removable cloth bag 49 (Fig. 7).

Support for the hat to be worked upon and oval lathe for driving said hat

The hat is fixed on a block 50 (Figs. 6 and 8) which is fixed on a spindle 51 by a fixation device which is preferably made as follows: in block 75

50 is fixed a flanged tube 52. Said tube 52 is adapted to slide on spindle 51. Two balls or fingers 53 (Fig. 8), or any equivalent device, pushed by a spring 54, project from the surface of said spindle 51. Said balls or fingers 53 disappear under the effect of the pressure of tube 52 when block 50 is pushed.

The length of said tube 52 is smaller than that of spindle 51, so that, when the base of the block 10 bears against a plate 55 integral with spindle 51, balls 53 or any other equivalent organs again project from the surface of the spindle and prevent tube 52 from escaping.

A stud 56 extending through a suitable hole 15 of the flange of tube 52 ensures the correct positioning of the block and its drive.

That mode of fixation, viz, centering by means of a bore and locking by means of an extensible device, may, of course, be applied to all kinds of 20 machines used in the hat making industry.

The oval lathe which supports block 50 is so constructed as to be wholly enclosed in a casing containing an oil bath. Spindle 51—51^a (axis A of the mechanism) carries, at its rear part, an 25 inside gear 57. Said spindle 51—51^a is journalled in an oscillating head 58 (rod ABC). Said head is provided with two parallel plane faces 59 and 59^a, which are adapted to slide between two parallel faces, one of which belongs to casing 60 and the other to a plate 61 which closes casing 30 60. Oscillating head 58 carries an axis 62 (axis C) (Figs. 8 and 9), through which it is jointed to a sliding member 63. Said sliding member 63 is guided by two rectilinear horizontal guides 64 (straight line) (Fig. 9) integral with casing 60. 35

A circular piece 65, rigid with oscillating head 58, slides on the front plane face of casing 60 and constantly closes the aperture of said casing during the motion of oscillating head 58. A piece 40 66 is keyed in head 58. Said piece 66 comprises a bore in which is engaged a journal 67 (axis B) of a piece 68. Said piece 68 carries a pinion 69 (Fig. 8) which is keyed thereon and meshes with inside gear 57 and has a number of teeth equal to one half that of said gear. At the rear, piece 68 is provided with an oblique projection 45 70. Said part 70 is adapted to slide in the oblique channel of a piece 71. Said piece 71 is adapted to slide along axis E (Fig. 8) of the bore 72 of a 50 cylindrical piece 73. Studs 74 (Fig. 8), fixed in piece 71 and adapted to slide in grooves 75 of piece 73 serve to connect said piece 71 with a piece 76 disposed outside of tube 73.

Said piece 71 is actuated by a fork 79, keyed 55 on a vertical shaft 80, through the intermediary of a stop 77—73—78.

Piece 73 carries at its front end a helicoidal wheel 81 adapted to mesh with a screw 82. On the shaft 83 of said screw is keyed a pulley 84 60 driven through any suitable means, for instance by a belt 85 (Fig. 6), from any suitable motor 86, of the electric or any other type, which may, for instance, be supported by frame 87.

The operation of the oval lathe is as follows: 65 Motor 86 drives, through screw 82 and wheel 81, piece 73, which embodies axis E of the mechanism of Fig. 2. Said axis E, whose eccentricity with respect to axis B (journal 67) is adjusted by the displacement of block 71 in piece 73, drives 70 said axis B, and axis A (spindle), through pinion 69 and inside gear 57. Axis E traces, in a plane moving together with axis A, a hypocycloid which, in this particular instance, is an ellipse. The center of the pouncing pad, which is located on 75 straight line L, describes on the piece driven by

spindle A a curve parallel to said ellipse, which is an oval exactly similar to the ovals utilized in the hat making industry. By suitably choosing the dimensions of the various organs and the eccentricity of axis B with respect to axis E, block 50 is moved in such manner that the various oval sections of said block are presented tangentially to the pouncing tool in the suitable direction, position and speed. In other words, the speed of the felt in contact with the pouncing tool is about 10 inversely proportional to the radius of curvature of the oval.

Connecting organs between the mechanisms above described

The machine is completed by organs for connecting together the mechanism for driving the block and the mechanism for driving the pouncing tool.

According to the embodiment shown, a pinion 20 88 is keyed on the rear part of tube 13 (Figs. 6, 8 and 10). A piece 90 is adapted to oscillate concentrically with a shaft 94. Said piece 90 carries two pinions 91 and 92 (Fig. 10) mounted loose thereon and meshing with each other. Pinion 92 25 is constantly in mesh with a pinion 93 keyed on shaft 94.

As shown in Fig. 10, the piece 90 is constantly subjected to the action of a spring 95. This spring also causes pinion 91 to mesh with pinion 30 93. A rod 96 (Figs. 6, 10 and 11) is operative to displace piece 90 in an upward direction, to the position shown in Fig. 10, to disengage pinions 91 and 93, and to mesh pinions 92 and 93.

Said rod 96 carries at its lower end a stop 97, 35 which can come to rest upon a pawl 98 provided with a projection 98' keyed on a shaft 99 (Fig. 11). A rod 100, in line with rod 96, is provided with a stop 101, which can be engaged by pawl 102 provided with a projection 102', pivotally mounted 40 about an axis 103 and which may also raise stop 97.

Rod 100 carries a bar switch 104 and another stop 105 (Fig. 6). It is jointed at its lower end, at 106, to a pedal lever 107. A spring 108 constantly tends to move said rod 100 in a downward direction.

Furthermore, shaft 94, on which is keyed pinion 93 (Figs. 8 and 10), is provided with a screw 109, which meshes with a toothed wheel 110 (Fig. 50 6) keyed on a vertical cam shaft 111. Said shaft 111 has, keyed on it, successively, in the downward direction, two fingers 112, 113 (Figs. 6 and 13), adapted to cooperate with the projections 98' and 102' the support 114 of an oval cam 115 55 (Figs. 6 and 13), the support 116 of a cam 117 for regulating the pressure and the speed of the pouncing tool (Figs. 6 and 12), and, finally, a pinion 118 (Fig. 6) which, through a toothed wheel 119, transmits the movement of shaft 111 60 to pinion 27 of the tool driving mechanism.

Cam 115 (Figs. 6 and 13) and cam 117 (for regulating the pressure and the speed of the pouncing tool, Figs. 6 and 12) are removable. They are, for instance, cut in sheet iron and fixed 65 in any suitable manner on the supports 114 and 116 keyed on shaft 111.

On removable cam 115 (Figs. 6 and 13) rests a roller 120, carried by a lever 121, keyed on shaft 80, which carries, at its upper end, keyed 70 70 thereon, fork 79, which serves to control the variation of the eccentricity of axis B with respect to axis E.

On removable cam 117, for varying the pressure and the speed of the pouncing, or other tool, 75

rests a roller 122 (Figs. 6 and 12) mounted loose on shaft 123, carried by a lever 124, which is mounted loose on shaft 80. A lever 125 (Fig. 6) bears against the lower end of axis 123. Said lever 125 is pivoted at an intermediate point at 126, on a lever 127. Said lever 127, which is pivoted at 128 on the frame, rests through its end 129 on the motor 45 which drives the tool. Lever 127 carries an arm 130, in which is screwed a screw 131, which makes it possible to compress a spring 132 between it and the free end of lever 125.

Finally, lever 124, which carries roller 122, which cooperates with cam 117, controls, through a chain 133, or any other similar device, a rheostat 134 disposed in the feed circuit of the motor 45 of the tool.

Operation of the whole machine

Block 50, on which is stretched the hat that is to be worked upon, being placed on spindle 51, the workman depresses pedal 107. He thus compresses spring 108 and raises rod 100 and tube 101. The latter pushes rod 96, which moves piece 90 upwardly and causes wheel 92 to mesh with pinion 88. The two pawls 98 and 102 engage stops 97 and 101 and maintain rod 96 and piece 90 in the raised position. During its upward displacement, rod 100 has driven, together with its bar, switch 104, which causes electric current to flow through motors 86 and 45.

The machine has thus been started and the pouncing tool, driven by shaft 111 and transmission 118-119-27, moves from the base of the block to its top, but, as above explained, owing to the action of the hypocycloidal mechanism according to the invention, axis 6 (O) remains constantly tangent to the hypocycloid M-N-P (Fig. 2) and the plane of the pouncing tool which is parallel thereto remains substantially tangent to said hypocycloid, the variation of speed along said hypocycloid being corrected by pinion 27 and crank 24.

Simultaneously, the oval lathe mechanism enclosed in casing 60 moves block 50 in such manner that the oval section of said block opposite the pouncing tool may be presented in a tangential position with respect to said tool, and, owing to the dimensions of the oval lathe mechanism, with a variable speed at each point of said oval, said speed being substantially inversely proportional to the radius of curvature at the point of said oval that is in contact with the pouncing tool.

In connection with the displacement of the pouncing tool, cam 115 varies the position of piece 71 and, consequently, the eccentricity of axis B and that of the oval.

It results therefrom that the pouncing tool remains always substantially in the tangent plane at each point of the surface of the block.

Simultaneously, cam 117 applies, with variable strength, the end of axis 123 on lever 125. The latter compresses more or less spring 132 and therefore tends to lift more or less the end of lever 129, which is in contact with the casing of the pouncing tool, and therefore to diminish or increase the pressure of the pouncing tool on the hat. Simultaneously, cam 117 produces a variation of the rheostat 134, so as to reduce the speed of motor 45 at the same time as the pressure of the pouncing tool against the hat is reduced. Besides, the speed of motor 45 may be modified by acting manually on a rheostat.

When the pouncing tool reaches the top of the hat, finger 112 moves pawl 98 aside through the

projection 98', rod 96 moves down and, under the action of spring 95, piece 90 pivots and causes wheel 91 to mesh with pinion 88. This has for its effect to reverse the motion of the pouncing tool, which therefore comes back to its starting position. When said tool reaches said position, finger 113 pushes pawl 102 through the projection 102' and releases rod 100. Said rod moves downwardly under the action of spring 108 and switches off the electric current which stops motors 86 and 45. Stop ring 105 exerts a downward pressure on lever 127, which causes the casing of the pouncing tool to pivot about axis 6 (C) and to move pouncing pad 33 away from the hat. The machine is therefore stopped and it suffices to exert a traction in order to remove block 50 which carries the hat.

The abrasive paper may be fixed to a removable pouncing pad, according to the embodiment shown in Fig. 14. The abrasive paper is cut into small pieces 135 and fixed by means of any appropriate substance, such as gum, gelatine, or a rubber solution, on a supple leather or rubber band 136 (elastic, preferably). Said band 136 is placed around a spongy rubber pad 137, which lies in a light sheet iron box 138. Said box 138 is provided with a device for securing it promptly onto tube 31. For instance, said box 138 fits into a corresponding conical box 139, which is soldered onto tube 31. A nut 141, which secures the two boxes tightly together, is screwed onto a screw pin 140, fixed to box 138.

The device may also comprise means to insure a uniform and slow continuous forward motion of the pouncing pad, when the latter is displaced on the side of the hat, and a continuous speed progressively accelerated when said pouncing pad is displaced from the rounded part to the top of the hat.

For instance, the transmission of the forward motion between shaft 80 and pinion 21 may be insured in place of the members (22, 28, 24, 25, 26, 27, 119, 118) illustrated Fig. 6, as indicated in plan in Fig. 15: shaft 80 is provided with a circular part 118a, keyed to the lower part of said shaft 80. Said circular part 118a is in an eccentric position with respect to axis 80 and it comprises a journal and a plurality of teeth. A connecting rod 142 is jointed, at one end, to the journal of circular part 118a and, at the other end, to the axis of crank 143. Said crank 143 is mounted loose about stationary axis 19-A. Connecting rod 142 is provided with a spindle 144. Two intermediate toothed wheels 145 and 146, meshing together and respectively with the teeth of piece 118a and of pinion 21, transmit the rotary motion of shaft 80 to pinion 21.

The eccentricity and the relative position of piece 118a are selected with a view to insuring, through the action of the eccentric pinion combined with the differential movements of the gears with respect one to the other, a continuous and approximately uniform displacement of the pouncing pad when on the side of the hat and a progressively accelerated displacement of said pad when it moves about the rounded part of the hat and towards the top of same.

The machine may further comprise a safety device to switch off the electric current which feeds the motors of the machine, when the pouncing tool accidentally passes beyond the fingers 112 and 113 which limit its displacement i. e. when the moving aside of pawl 98 has not caused the reversing of the motion of the tool, or when the moving aside of pawl 102 has not caused the stop-

ping of the motor, thus avoiding a possible rupture of the organs of the machine.

Fig. 16 illustrates, on a larger scale, a modification of Fig. 11, showing by way of example such a safety device. Each switch consists, as is well known, of a glass tube 146 in which two electrodes are soldered, said glass tube 146 containing a certain mass of mercury. When the tube is in the horizontal position, the two electrodes are immersed in the mercury and the contact is established. When the tube drops, the current is switched off. The switches are fixed to an oscillating part 147 which, left to itself, is tilted, under the action of its own weight, thus actuating the switches and, therefore, switching off the current. Said oscillating part 147 is moved up, back to its original position, through the action of pin 148, which slides in cylinder 149 and is subjected to the action of a spring 150, which tends, normally, to raise said screw pin 148. Said cylinder 149 is fixed to stop 101 mounted upon rod 100. Therefore, by depressing pedal 107 (Fig. 6), the raising of rod 100, of cylinder 149, of piston 148 and of oscillating part 147 is produced and the contact is established.

Pawl 98 and 102 are provided with arms 98^a and 102^a, disposed, as shown in Fig. 16, on both sides of part 147. If the pouncing tool, as a body, accidentally passes beyond either of the limits of its displacement, one of the stops 112, 113 (Figs. 6 and 13) pushes the corresponding pawl 98 or 102 through the medium of projections 98' and 102' and swings it down. The arm of said pawl 98 or 102 comes into contact with part 147, also swinging it down by compressing its spring 150. The result is that the feeding current is switched off and the machine stops automatically without further damage.

To start it off once more, after having attended to the cause of the stop, it will be sufficient to turn it by hand in the direction opposite to that of its previous motion; this brings the pawls back to their normal position.

Of course, any tooth, brush, velvet surface, iron, revolving wheel provided with wool or with abrasive paper, or the like, might be substituted for the pouncing tool, which is removably mounted.

While I have disclosed what I deem to be preferred embodiments of my invention, it should be well understood that I do not wish to be limited thereto, as there might be changes made in the arrangement, disposition and form of the parts, without departing from the principle of my invention as comprehended within the scope of the appended claims.

What I claim is:

1. A hat working mechanism of the type described comprising in combination, a cinematic mechanism including a rigid member, two parallel spindles journaled in said member, a third spindle parallel to the two above mentioned spindles, located in the same plane as said spindles and also journaled in said member, transmission means for connecting the two first mentioned spindles to one another, whereby they are caused to rotate one with respect to the other at respective speeds of revolution whose ratio is equal to the reciprocal of the ratio of the respective distances from said two spindles to the third mentioned spindle, said speeds of revolution and said distances being counted algebraically, a fourth spindle rigidly connected to one of the two first mentioned spindles and parallel thereto, a rigid member to which the fourth spindle is journaled,

said last mentioned rigid member being adapted both to slide and rotate with respect to the third mentioned spindle, a tool supported by said last mentioned rigid member so as to move along a hypocycloid corresponding substantially to a section of the hat by a plane at right angles to its base, a second cinematic mechanism of the same type, a block for supporting the hat adapted to be actuated by the last mentioned mechanism, and means for connecting said two mechanisms to one another adapted to maintain the tool in a tangential position with respect to the piece of work.

2. A hat working mechanism according to claim 1 further comprising a spindle supported by the last mentioned rigid member and adapted to rotatively support the tool, a motor for driving the tool, said motor being so arranged as to form a counterweight adapted to press the tool against the hat.

3. A hat working mechanism according to claim 1, further comprising a spindle supported by the last mentioned rigid member and adapted to rotatively support the tool, a motor for driving the tool, a fly-wheel driven by said motor having its axis at right angles to said spindle, said fly-wheel being adapted to brake the rebounding movements of the tool with respect to the hat, through a gyroscopic effect.

4. A hat working mechanism according to claim 1 comprising a spindle supported by the last mentioned rigid member and adapted to rotatively support the tool, and elastic means interposed between said last mentioned spindle and said tool.

5. A hat working mechanism according to claim 1 further comprising a counterweight for pressing the tool against the hat, a lever resting upon said counterweight, a spring acting upon said lever, and a cam adapted to act upon said lever against the action of said spring, whereby the pressure of the tool against the hat can be adjusted at will.

6. A hat working machine according to claim 1, further comprising, a motor for driving the tool, a rheostat for controlling the feed circuit of said motor, a cam, means for connecting said cam to said rheostat, whereby the speed of the tool may be varied as a function of its displacement.

7. A hat working machine according to claim 1, further comprising, a metallic cylindrical tube for carrying said tool, a fluid tight casing, an element pivoted in said casing adapted to guide said metallic tube, a crank jointed to said metallic tube, two symmetrical counterweights for balancing said crank and an electric motor carried by said casing for driving said crank.

8. A hat working machine according to claim 1 further comprising a counterweight for pressing the tool against the hat, a lever resting beneath said counterweight, a spring acting upon said lever, a cam adapted to act upon said lever against the action of said spring, whereby the pressure of the tool against the hat can be adjusted at will, a spindle carrying the hat supporting block, a motor for driving said spindle, a cam driven by said motor, a guiding piece controlled by said cam, and an oblique tail adapted to slide in said guiding piece for adjusting the eccentricity of said spindle, and a common shaft for carrying said cams.

9. A hat working machine according to claim 1 further comprising a counterweight for pressing the tool against the hat, a lever resting beneath

said counterweight and adapted to actuate same, a spring acting upon said lever, a cam adapted to act upon said lever and said spring, thereby compressing said spring to urge the tool against 5 the hat with a determined pressure, a spindle carrying the hat supporting block, a motor for driving said spindle, a cam driven by said motor, a guiding piece controlled by said cam, an oblique tail adapted to slide in said guiding piece for adjusting the eccentricity of said spindle, a common shaft for said cams and supporting means for securing said cams on said shaft.

10. A hat working machine of the type described comprising in combination, a cinematic mechanism including a rigid member, two parallel spindles journaled in said member, a third spindle parallel to the two above mentioned spindles, located in the same plane as said spindles and also journaled in said member, transmission means 20 for connecting the two first mentioned spindles to one another, whereby they are caused to rotate one with respect to the other at respective speeds of revolution whose ratio is equal to the reciprocal of the ratio of the respective distances from said 25 two spindles to the third mentioned spindle, said speeds of revolution and said distances being counted algebraically, a fourth spindle rigidly connected to one of the two first mentioned spindles and parallel thereto, a rigid member to which the 30 fourth spindle is journaled, said last mentioned rigid member being adapted both to slide and rotate with respect to the third mentioned spindle, a tool supported by said last mentioned rigid member, a second cinematic mechanism of the same 35 type, a block for supporting the hat adapted to be actuated by the last mentioned mechanism, a motor, for driving the last mentioned mechanism, a reversing gear, a cam shaft driven by said motor, a clutch mechanism controlling said reversing 40 gear, a plurality of arms carried by said shaft for acting upon said clutch mechanism, in order to cause the tool to move along two quarters of an hypocycloid, so that it is moved from the base of the hat up to the top thereof, and then back to 45 the base, at which time the clutch is released.

11. A hat working machine according to claim 10 further comprising a rod connected to said reversing gear, a pedal for controlling said rod, a circuit breaking device connected to said rod for 50 switching off the feed current of said motor, stop means provided on said rod, a plurality of pawls operatively connected to said arms of said shaft, and adapted to engage said stop means so as to release said rod, and antagonistic spring devices 55 adapted to act on said rod against the action of said pedal.

12. A hat working machine according to claim 10 further comprising a counterweight for pressing the tool against the hat, a lever resting beneath 60 said counterweight for actuating same, a spring acting upon said lever, a cam adapted to act upon said lever and said spring, thereby compressing said spring to urge the tool against the hat with a determined pressure, a rod connected to said 65 reversing gear, a pedal for controlling said rod, a circuit breaking device controlled by said rod for switching off the feed current of said motor, stop means provided on said rod, a plurality of pawls operatively connected to said arms of said 70 shaft, and adapted to engage said stop means so as to release said rod, antagonistic spring devices adapted to act on said rod against the action of said pedal, a stop carried by said rod for moving the tool supporting mechanism away from the 75 hat, and bringing it into contact with said lever.

13. A hat working machine according to claim 1 further comprising electric motors for driving the tool mechanism and the hat supporting block mechanism, stops for limiting the displacement of the tool, and a safety device for switching off the current of said motors when the tool moves accidentally beyond said stops.

14. In a hat working machine, a block for supporting the hat, a tool, a mechanism driving the tool and adapted to cause its plane to remain tangent to a section of the hat at right angle to its base, a mechanism driving said block and adapted to present the sections of the hat parallel to its base in a tangential position with respect to said plane, connecting means between said two mechanisms adapted to coordinate their movements, said mechanism driving the tool comprising a cinematic mechanism including a rigid member, two parallel spindles journaled in said member, a third spindle parallel to the two above mentioned spindles, located in the same plane as said spindles and also journaled in said member, transmission means for connecting the two first mentioned spindles to one another, whereby they are caused to rotate one with respect to the other at respective speeds of revolution whose ratio is equal to the reciprocal of the ratio of the respective distances from said two spindles to the third mentioned spindle, said speeds of revolution and said distance being counted algebraically, a fourth 20 spindle rigidly connected to one of the two first mentioned spindles and parallel thereto, a rigid member to which the fourth spindle is journaled, said last mentioned rigid member being adapted both to slide and rotate with respect to the third 25 mentioned spindle.

15. In a hat working machine, a tool, a metallic cylindrical tube for carrying said tool, a fluid tight casing, an element pivoted in said casing adapted to guide said metallic tube, a crank 40 jointed to said metallic tube, two symmetrical counterweights for balancing said crank and an electric motor carried by said casing for driving said crank.

16. A hat working machine according to claim 1, further comprising a crank and link device actuating the tool and guided at a point which does not coincide with the center of the tool.

17. A hat working machine according to claim 1, in which the hat supporting block is provided with a recess, further comprising a spindle carrying said block and carried by the last mentioned cinematic mechanism, an expanding device on said spindle and a conically shaped member co-operating with said expanding device, in order to withdraw latter when the block longitudinally slides upon the spindle.

18. A hat working machine according to claim 1, further comprising a counterweight for pressing the tool against the hat, a lever resting beneath said counterweight and adapted to actuate same, a spring acting upon said lever, a cam adapted to act upon said lever and said spring, thereby compressing this latter and adjusting thus the pressure of the tool against the hat, a 65 spindle carrying the hat supporting block, a motor for driving said spindle, a cam driven by said motor, a guiding piece controlled by said cam, an oblique tail adapted to slide in said guiding piece for adjusting the eccentricity of said spindle, a 70 common shaft for said cams and supporting means for securing said cams on said shaft, said last mentioned shaft being positively connected to and driving said first cinematic mechanism.

19. A hat working machine according to claim 75

10, further comprising a vertical shaft a pinion eccentrically mounted upon said shaft, a gear wheel meshing with said pinion, a link connecting the axes of said gear wheel and pinion, a crank 5 cooperating with said link, a plurality of gear wheels mounted on said crank and link, and transmitting the movement of said eccentrically mounted pinion to the mechanism actuating the tool, the setting of said eccentrically mounted 10 pinion being such as to move the tool continuously at a slow speed along the sides of the hat and at a progressively increasing speed along the top of the hat.

20. A hat working machine according to claim 15 22, further comprising a vertical shaft a pinion eccentrically mounted upon said shaft, a gear wheel meshing with said pinion, a link connecting the axes of said gear wheel and pinion, a crank 20 cooperating with said link, a plurality of gear wheels mounted on said crank and link, and transmitting the movement of said eccentrically mounted pinion to the mechanism actuating the tool, the setting of said eccentrically mounted 25 pinion being such as to move the tool continuously at a slow speed along the sides of the hat and

at a progressively increasing speed along the top of the hat.

21. In a hat working machine, a rod, a box of sheet metal, a spongy rubber pad in said box, a removably mounted yielding band surrounding 5 said pad, and pouncing paper fixed upon said band, whereby said paper is yieldingly applied against the surface of the hat.

22. In a hat working machine, a block for supporting the hat, a tool, holding means to 10 which said tool is positively secured and with respect to which it cannot move, a mechanism for driving together said tool, and holding means, comprising a device for positively guiding said tool tangentially over the hat surface, a lathe 15 mechanism driving said block and connecting means between said two mechanisms adapted to coordinate their movements, said mechanisms while cooperating causing the operative surface of said tool to be displaced always and simultaneously along two sections of the hat, one of these sections being parallel to the hat base and the 20 other one being perpendicular thereto.

MARCEL CASSÉ.
